UNITED STATES PATENT OFFICE.

CARL BRANDT, OF BOSTON, MASSACHUSETTS.

DESIGN FOR A HAT-SWEAT.

43,251.

Specification for Design.

Patented Nov. 19, 1912.

Application filed August 23, 1912. Serial No. 716,752. Term of patent 7 years.

To all whom it may concern:

Be it known that I, CARL BRANDT, a citizen of the United States, residing at Boston, in the county of Suffolk and Commonwealth of Massachusetts, have invented a new, original, and ornamental Design for Hat-Sweats, of which the following is a specification, reference being had to the accompanying drawing, forming part thereof.

The figure of the drawing is a front elevation of a hat sweat showing it flattened out.

I claim:

The ornamental design for a hat sweat as shown.

In testimony whereof, I have signed my name to this specification, in the presence of two subscribing witnesses.

CARL BRANDT.
